PULP STOCK AGITATION

John A. Rosmaat, Manistee, Mich.

Application May 31, 1935, Serial No. 24,265

19 Claims. (Cl. 92—37)

This invention relates to paper manufacture and more particularly to an improved method and apparatus for storing and agitating paper pulp stock.

In the manufacture of paper it is necessary at times to store the paper pulp stock in large storage tanks or chests. The pulp stock is mixed with a large amount of water, and if left unagitated will either settle to the bottom of the body of water or float to the top depending upon the type of pulp stock employed. This destroys the uniformity of the pulp stock mixture and results in poor and unpredictable grades of paper.

In the past attempts have been made to agitate the pulp stock stored in chests by means of paddle agitators. These devices were relatively expensive to install and operate, and only agitated that part of the pulp stock immediately adjacent thereto. Furthermore, a plurality of these paddle agitators were required to extend into the chest and this awkward construction plus the lubrication required upon the operating parts obstructed and contaminated the pulp stock.

Agitation of the contents of a pulp stock chest must be thorough and complete. If this is not provided or if the agitation is improperly furnished, dead deposits or immovable islands of pulp stock will form in the chest which not only take up storage space reducing the capacity of the chest but also sour and contaminate new pulp.

It is an object of this invention to provide a storage tank or chest for pulp stock or the like which provides a thorough and complete agitation of the pulp stock. In accomplishing this object a circulatory system of improved design is associated with the chest and compels continuous movement of all of the pulp stock through the chest.

Another object of this invention is to provide a circulatory system for the pulp stock which is inexpensive to install and operate and which does not require the presence of movable parts in the chest. A further object is to provide a storage chest of such a construction that there is no necessity for long floor pitches, midfeathers, or intermediate supports in the interior of the chest which would obstruct the free flow of the pulp stock, retard its circulation, and reduce the chest capacity for a given size chest.

A meritorious feature of the invention resides in the novel formation of a deflector or baffle for directing the flow of the pulp stock to those areas in the chest where dead deposits of the stock are likely to form. Another meritorious feature re-

sides in the improved manner of introducing new pulp stock which quickly mixes the same with the older stored stock.

The invention comprises essentially a large storage tank or chest through which pulp stock is continually passed in one direction and recirculated. A circulatory system is associated with the chest and is arranged to discharge pulp into one end of the chest and withdraw it from the other end thereby enabling the pulp stock to flow uniformly in one direction from one end to the other end of the chest. Positioned within the chest is a diverting baffle or deflector which is adapted to direct the flow of pulp stock to those areas and corners of the chest where, if such deflector were not used, the pulp stock would be likely to deposit and clog the chest.

Beaters are associated with said chest and communicate therewith through conduits which empty into the circulatory system prior to re-entrance of the stock into the contents of the chest. The circulatory system is provided with a by-pass for discharging fluid or stock upon the deflector while the other end of the chest is being cleaned.

Other features and advantages of the invention will appear from the detailed description which will now be given in conjunction with the accompanying drawings, in which:

Figure 1 is a cross-sectional view showing the interior of the stock chest and the relation of the beaters to the chest.

Fig. 2 is a top interior view of the chest along line 2—2 in Fig. 1.

Fig. 3 is a view partly in cross-section showing a modification of the apparatus, and

Fig. 4 is a cross-sectional view along line 4—4 of Fig. 1.

A stock chest 10 for storing pulp stock is associated with a plurality of beaters 12 from which it receives pulp stock in the manner to be described hereinafter. The chest may be made of reinforced concrete construction as indicated in the drawings or of any suitable material. The chest may be cast as monolith extending from floor level 11 to floor level 13 thereabove. As illustrated in the drawings the chest forms an actual part of the building. The chest is provided with a floor 14 sloping from one end of the chest to the other and a recess or depression 16 is formed in the floor adjacent to its lower end. The side and end walls of the chest round into the bottom or floor of the chest as indicated in the drawings.

The apparatus for continuously circulating the

pulp stock into and out of the chest will now be described. This apparatus causes the pulp stock to flow uniformly in one direction through the chest from the higher end to the lower end of the chest. Maximum storage area for each given size of chest is provided by such procedure. There is no necessity for long floor pitches, or mid-feathers or intermediate supports. The pulp stock flows uniformly and uninterrupted from one end of the chest to the other.

A pump 18 is located outside the chest, and by means of the suction tube 20 withdraws pulp stock from the recess 16 to be forced by the pump through the discharge pipe 22. This pipe in turn is connected to the reduced end of a mixing flow tube 24 which extends lengthwise through the chest to discharge at the opposite end of the chest. This tube gradually increases in diameter as it approaches its discharge end as is clearly apparent in the drawings. The chest proper, the suction tube 20, the pump discharge pipe 22 and the flow tube 24 form a circulatory system through which the pulp stock is constantly delivered. The continuous movement of the pulp stock through this system agitates the stock and prevents the formation of dead and immovable deposits of the stock within the chest. Motor 26 drives the pump, and valve means 28 may be provided for controlling the volume of pulp stock circulated.

Depending from the tube 24 at the low end of the chest floor is a deflector or baffle 30 of a generally V-shape configuration with the apex of the deflector facing into the flowing pulp stock. The angularly disposed sides 32 of the deflector direct the flow of pulp stock outwardly against the side walls of the chest at the low end of the chest. As shown in Fig. 1 the baffle slopes from top to bottom in the direction of stock flow and terminates within the recess 16. The sides 32 are of less width at the top and gradually increase in width as they approach the bottom. At the base of each side a slot or aperture 34 is formed for permitting a portion of the pulp stock to flow therethrough and into the region in the rear of the deflector. The deflector is constructed to fit around the flow tube at its upper end. It is obvious that additional spreader or deflector means may be provided if desired. These may be positioned substantially along the longitudinal median line of the chest or to one side or the other to cause lateral divergence of the stock flow.

A spout or pipe 36 is arranged to by-pass pulp stock or fluid to flow through the tube 24 downward upon the sloping sides 32 of the deflector. Butterfly valves 38 and 40 are provided in the tube 24 and spout 36 respectively. These valves are coupled together by appropriate lever mechanism so that when one is closed the other is open. The manual control of these valves is indicated at 42. Normally valve 40 in the by-pass is closed, but when it is desired to flush and clean the interior of the tank the valves may be operated to by-pass the fluid contents of the tube 24 downward upon the inclined parts of the deflector.

The beaters 12 communicate with the chest 10. The preferred manner of such communication is by way of the flow tube 24. As shown in the drawings, valved conduits 44 lead from each of the beaters and empty into the tube 24. The beater to the extreme left in Fig. 2 is shown as emptying directly into the chest. By directing the contents of the beaters into the mixed con-

tents of the flow tube 24 a preliminary mixing is obtained before the stock is discharged into the tank.

By sloping the floor of the chest from one end to the other a hydraulic gradient in the direction of the flow of the stock is produced. The flow is unobstructed and in one direction. The diverting or deflecting device 30 is arranged to assist in the established law of flow through centrifugal or axial flow pumps in which the pump capacity increases with decreased head. The deflector is narrowest at the top and offers less resistance to the flow of the stock at the higher levels. Being wider adjacent the bottom, it offers greater resistance and more thorough agitation by forcing the lower levels of the chest contents to pass further around before being withdrawn from the chest by the pump. The deflector or baffle is located at substantially the point of highest velocity of flow, and the stock instead of flowing at this point of highest velocity into the pump suction, it is diverted around the deflector before it can enter the suction tube thereby pulling on the stock and forcing it to split its flow lines around and under the deflector and thence into the pump suction.

The discharge or flow tube 24 is constructed with an increasing area from inlet to outlet and serves to reduce the total pumping head as well as permit the stock to roll over and over in its course through the flow tube. When the pulp stock discharges from the flow tube it spreads out and piles up to create a head and furnish the hydraulic gradient for the flow of the stock down the chest toward the pump suction. The pump should be of a type to handle a large volume at a very low discharge head.

When it is desired to wash out the chest, the by-pass is regulated to direct the discharge of the pulp stock upon the baffle where it flows down the inside and is contained in the lower part of the chest. This allows the upper end of the chest or about 75% of it to be washed and cleaned while the stock from the lowest end of the chest circulated through the by-pass and pumped out and used up in the next operation.

In the modification illustrated in Fig. 3 there is shown a stock filter 50 which delivers stock in a continuous stream into one end of the chest. It is removed from the other end of the chest by a pump and recirculated through tube 24 in the same manner as described above.

What I claim is:

1. The method of delivering pulp stock to a storage chest and agitating the same therein which comprises pumping the pulp from a low part of the storage chest and reintroducing it into the chest at a high part thereof to establish a circulatory system including the chest as a part thereof, and delivering additional pulp stock into the circulatory system prior to the reintroduction of the stock into the chest.

2. A storage chest for pulp stock and apparatus for agitating the pulp stock therein comprising, in combination, an elongate chest, a flow pipe extending substantially the length of the chest along its upper level and having its discharge end terminating in the chest, means for withdrawing pulp stock from the lower levels of the chest and delivering the same to the flow pipe to be discharged thereby into the chest, a deflector extending downwardly from the flow pipe intermediate the ends of the chest, and valve means for by-passing the contents of the flow tube downward upon said deflector.

3. In combination with a storage chest for pulp stock, a tube extending into the chest and adapted to convey pulp stock therethrough and discharge the same into the chest, a deflector in said chest, and means for withdrawing pulp stock flowing through said tube before it reaches said discharge and directing the same upon said deflector.

4. In the manufacture of pulp stock, a storage chest, a flow tube disposed along the upper level of said chest, means for circulating the pulp stock in said storage chest through said flow tube, a plurality of beaters associated with said chest, and means for emptying the contents of said beaters into said flow tube to mix the same with the pulp stock flowing through the tube prior to its discharge into the tank.

5. In a storage chest for pulp stock, a deflector disposed angularly to the flow of the pulp stock through said chest, said deflector having an aperture adjacent its lower extremity through which a portion of the pulp stock may flow to prevent the collection of non-flowing pulp stock behind the deflector.

6. In the manufacture of paper pulp, a storage chest having an inclined bottom from one end thereof to the other, said bottom provided with a recess adjacent the lower end of the chest, means for discharging pulp stock into the chest at the higher end of the chest, means for withdrawing pulp stock from said recess in the lower end of the chest thereby creating a continuous flow of pulp stock from the higher end to the lower end of the chest, and a deflector located adjacent said recess and arranged to divert the flowing pulp stock outwardly around the same and toward the corners of the chest prior to its withdrawal from the chest.

7. In the manufacture of paper pulp, a storage chest for pulp stock having a sloping bottom extending from a higher level at one end of the chest to a lower level at the other end of the chest, a tube disposed adjacent the top of said chest having its discharge end terminating adjacent the higher end of the chest, means for withdrawing pulp stock from the lower end of the chest and delivering the same to said tube to be discharged therefrom into the chest, a deflector positioned in said chest for diverting the flow of the stock through said chest into those areas where dead deposits of stock may form, means for by-passing the fluid contents of said tube upon said deflector, and means for introducing new pulp stock into said tube.

8. Apparatus for storing and agitating pulp stock comprising, in combination, an elongate chest having a bottom sloping from one end to the other, a flow tube disposed in the upper level of the chest having its discharge end terminating above the higher end of the sloping bottom, means for withdrawing pulp stock from the lower end of the chest and reintroducing it into the chest through said flow tube to provide a continuous flow of pulp stock through the chest from the higher end to the lower end, a V-shaped deflector mounted vertically in the chest spaced from the side walls thereof, said deflector having its apex facing into the flow of pulp stock splitting the flow laterally toward the side walls of the chest to prevent the formation of dead areas of pulp stock in the chest.

9. Apparatus for storing and agitating pulp stock comprising, in combination, a chest having a sloping bottom tending to drain the pulp stock contents toward one end thereof, means

for withdrawing pulp stock from the lower end of the chest and reintroducing the same into the chest at the other end providing a continuous unidirectional flow of pulp stock through the chest, a V-shaped deflector mounted vertically in said chest with the apex thereof facing into the flow of pulp stock, said deflector being of increasing width from the top to the bottom thereby offering greater resistance to the flow of stock and consequently causing greater deflection of the stock in the lower levels of the chest.

10. Apparatus for storing and agitating pulp stock comprising, in combination, a chest, means for flowing pulp stock through said chest, a V-shaped deflector mounted vertically in said chest between the side walls thereof having its apex facing into the flowing pulp stock, said deflector being wider adjacent the bottom of the chest and extending in closer proximity to the side walls of the chest to cause a greater divergence of that portion of the pulp stock flowing in the lower levels of the chest.

11. In the manufacture of pulp stock, a storage chest, a flow tube disposed along the upper level of the chest having its discharge end terminating adjacent one end of the chest, means for withdrawing pulp stock from the other end of said chest and returning the same to the chest through said flow tube, means for introducing new pulp stock into said flow tube, said flow tube being of increasing diameter as the discharge end is approached to cause the new and the old pulp stock to roll over and over together in their course through the tube providing a preliminary mixing of the new stock with the old well agitated stock prior to its introduction into the chest.

12. In the manufacture of pulp stock, a storage chest, a flow tube disposed along the upper level of the chest having its discharge end terminating adjacent one end of the chest, means for withdrawing pulp stock from the other end of the chest and returning the same to the chest through said flow tube, said flow tube being of increasing diameter as its discharge end is approached to cause the pulp stock to roll over and over upon itself in its course through the tube whereby a thorough mixing of the stock is provided.

13. Apparatus for storing and agitating pulp stock comprising, in combination, a storage chest, a pump having an intake communicating with the bottom of the chest to withdraw pulp stock therefrom and having a discharge communicating with the top of the chest to deliver pulp stock thereinto, said pulp discharge being of increased area as it approaches its outlet, and means for delivering additional pulp stock into that portion of the pulp discharge of increasing area to mix with the pulp stock flowing therethrough prior to discharge into the chest.

14. Apparatus for storing and agitating pulp stock comprising, in combination, a storage chest, a pump having an intake communicating with the bottom of the chest to withdraw pulp stock therefrom and having a discharge communicating with the top of the chest to deliver pulp stock thereinto, said discharge being provided with a flaring portion of increased diameter adjacent the discharge end thereof, and means for delivering additional pulp stock into said flaring portion of increased diameter through delivery conduits of substantially reduced diameter as compared with the diameter of the flaring portion.

15. Apparatus for storing and agitating pulp stock comprising, in combination, a storage chest, a pump having an intake communicating with the bottom of the chest to withdraw pulp stock therefrom and having a discharge communicating with the top of the chest to deliver pulp stock thereto, a baffle disposed within the chest adjacent to the pump intake adapted to cause the pulp stock flowing through the chest to spread outwardly toward the side walls of the chest before entering said pump intake. 5
16. Apparatus for storing and agitating pulp stock comprising, in combination, a chest for storing pulp stock, a circulatory system for withdrawing pulp stock from a low level within the chest and discharging the pulp stock so withdrawn into a high level within the chest including a discharge tube having an increased diameter adjacent its discharge outlet, and 10 means for delivering additional pulp stock into said tube for mixture with the circulated pulp stock flowing therethrough prior to the discharge of the same into the higher level of the chest. 15
17. Apparatus for storing and agitating pulp stock comprising a storage chest for pulp stock, pump mechanism communicating with a low part of the chest to withdraw pulp stock therefrom and with a high part of the chest to 20 deliver said withdrawn pulp stock thereto to establish a circulation of pulp stock through the chest, a sloping baffle within the chest shielding the outlet to said pump and adapted to direct the pulp stock flow through the chest toward the side walls of the chest, and means for by-passing a portion of the pulp stock withdrawn from the chest by the pump and discharging the same directly upon said baffle to flow thereover. 25
18. Apparatus for storing and agitating pulp stock comprising, in combination, a storage chest for pulp stock, means for moving pulp stock through said chest, a baffle structure disposed in the path of movement of said stock and having a deflecting surface against which the stock advances as it moves through the chest, said baffle structure provided with means for permitting a portion of said moving stream of pulp stock to pass therethrough and into the area on the side of the baffle structure opposite to said surface in order to prevent the accumulation of dead stock in said area. 30
19. Apparatus for storing and agitating pulp stock comprising a storage chest, a pump communicating with a low portion of the chest to withdraw pulp stock therefrom, said pump provided with an outlet terminating in a portion extending horizontally over the top of the chest, said horizontally extending portion of the outlet being of increasing diameter as its discharge end is approached. 35

JOHN A. ROSMAIT. 30
